RICHARD V. BUTLER, OF OLD FORGE, PENNSYLVANIA.

THREAD GUIDE FOR SPINNING MACHINES.

1,412,917.

Specification of Letters Patent. Patented Apr. 18, 1922.

Application filed June 21, 1921. Serial No. 479,338.

To all whom it may concern:

Be it known that I, RICHARD V. BUTLER, a citizen of the United States, and residing at Old Forge, county of Lackawanna, State 5 of Pennsylvania, have invented certain new and useful Improvements in Thread Guides for Spinning Machines, of which the following is a specification.

This invention relates to spinning machines and particularly to machines for spinning silk and its object is to provide a guide mechanism for use in combination with the usual feed rolls of such machines.

In silk spinning machines it is customary 10 to employ feed rolls arranged in pairs each pair comprising a front and rear roll arranged substantially parallel and mounted in a suitable frame. The threads of silk in any desired number are generally caused to 15 pass downwardly in front of the front roll and after being wound one or more times around each roll are led away from the front roll and caused to pass to other parts of the machine positioned beneath the rolls. It has 20 been found that when the threads are thus carried downwardly directed from the front roll or when they are allowed to pass over any considerable portion of such roll immediately before passing downwardly they 25 are liable to become entangled with the adjacent wraps of thread on the roll or to be caught by the front roll itself, with the result that the threads are wound about the rolls which necessitates stopping the rolls 30 and cutting the threads therefrom thus causing a loss of time as well as a loss of valuable material. My invention aims to overcome these difficulties by providing a guide mechanism which is arranged in front of 35 the usual rolls and so positioned as to receive the threads after they leave the rolls. This guide mechanism is so arranged as to lift or hold the threads out of contact or any extended contact with the front roll as the 40 threads are passing from the rolls to the guide and downwardly to the other mechanism of the machine.

One specific embodiment of the invention 45 is described in the following specification and illustrated in the accompanying drawings, in which:

Figure 1 is a side view showing a portion of a spinning machine containing the usual

feed rolls and also having my improved 55 guide mechanism attached thereto;

Figure 2 is a front view of the construction shown in Figure 1;

Figure 3 is a plan view of the same; and

Figure 4 is a sectional view on the line 4-4 of Figure 3. 60

Referring to the drawings in detail 10 represents a supporting member provided with side lugs 11 between which the roll carrying frame 12 is arranged, this frame being provided with front and rear bearings 13, 14, 65 within which the rolls 15 and 16 are rotatably mounted. These rolls are provided at their ends with gear teeth 17, 18, which mesh with a common driving gear 20 indicated by dotted lines in Figure 1. Between the rolls 70 15 and 16 there is arranged an inclined guide 21 which is suitably secured to the frame 12, this guide serving to keep the threads separated as they pass around the rolls. As shown in Figure 1 the threads are usually 75 led through a suitable guide 22 and into contact with the front roll 15 from which they pass around the rear roll 16 and after one or more turns about each of the rolls the threads are led downwardly to other parts 80 of the spinning machine.

The mechanism thus far described is old and well known. In my improved construction I provide a bracket 25 which is suitably 85 secured as by means of a bolt 26 to the supporting member 10, this bracket extending forwardly and upwardly and at its upper end being provided with spaced arms 27, 28 between which there is arranged a suitable guide 30. This guide is preferably made of 90 glass or porcelain or other suitable vitreous material and the same is positioned at an angle to the axis of the front roll 15, the purpose of such inclination being the same as that of the inclined guide 21 heretofore mentioned, namely it tends to keep the threads separated from each other thus avoiding entanglement of the same. The guide 30 may be rigidly secured in the arms 27, 28 or, if desired, may be rotatably mounted between 95 100 such arms.

By referring particularly to Figures 1 and 2, it will be observed that the upper surface or periphery of the front roll 15 is somewhat lower than that of the rear roll 16. The 105 guide 30 of my improved construction is

preferably arranged above the axis of the roll 15 and in substantially the same horizontal plane as the upper surface of the rear roll 16, the result being that the upper surface or periphery of the front roll 15 lies slightly beneath a straight line connecting the upper surface of the roll 16 and the guide 30. By this arrangement it will be apparent that as the threads leave the rolls and pass 10 to the guide 30 they will be lifted or held out of contact with the surface of the roll 15 and also held away from the adjacent wraps of the threads passing around said roll 15.

It will be understood that the terms 15 "front" and "rear" as applied to the rolls 15 and 16 are employed merely for convenience of description and are not to be taken as indicating any particular position of the rolls and the guide 30 in space. The 20 front roll may be regarded as the one arranged nearest the guide and the rear roll the one farthest from the guide. It is also to be understood that the axes of the rolls instead of being arranged in a horizontal 25 plane, as illustrated in the drawing, may be arranged in a plane inclined to the horizontal and that the particular angles at which the threads are led to and from the rolls are immaterial. 30 By thus lifting and holding the threads out of contact with the front roll 15 and away from the adjacent wraps of thread on the rolls, it has been found that the threads will not be caught by the rolls or become 35 entangled with adjacent threads. As heretofore noted, in the case of prior constructions such entanglement of the threads or catching of the same upon the rolls results in wrapping the material about the rolls 40 thus requiring that the machine or rolls be stopped until the entangled material can be cut therefrom. With my improved guide device applied to a machine these difficulties are largely avoided, the rolls can be operated 45 more steadily and require less attention and loss of time in cutting material from the rolls and loss of valuable material are to a considerable extent obviated.

Having thus described my invention what 50 I claim as new and desire to secure by Letters Patent is:

1. In a spinning machine having feed rolls and means for driving the same to wrap threads thereon, the improvement 55 which comprises a guide arranged adjacent one of said rolls over which guide the threads are adapted to pass when carried out of contact with the rolls, said guide being positioned above the axis of the roll adjacent which it is arranged.

2. In a spinning machine having feed rolls arranged side by side and means for driving the same, to wrap threads thereon, the improvement which comprises a guide 60 arranged adjacent one of said rolls over

which guide the threads are adapted to pass after leaving the rolls, said guide being positioned to hold the threads away from the roll adjacent to which it is arranged as the threads pass from the rolls.

3. In a spinning machine having feed rolls and means for driving the same to wrap threads thereon, the improvement which comprises a guide arranged adjacent one of said rolls over which guide the threads are 75 adapted to pass after leaving the rolls, the upper surface of said guide being arranged above the axis of the roll adjacent which the guide is mounted and positioned to hold the threads out of contact with said roll 80 as the threads pass from said rolls.

4. In a spinning machine, in combination, feed rolls about which threads are adapted to be wrapped, means for driving said rolls, a guide for receiving and guiding the 85 threads after they pass from said rolls, said guide being arranged adjacent one of said rolls and positioned above the axis of the roll adjacent which it is mounted.

5. In a spinning machine, in combination, 90 a front feed roll and a rear feed roll, means for supporting and driving said rolls to wrap threads thereon, a guide arranged in front of said front roll over which guide the threads are adapted to pass after leaving said rolls, said guide being positioned to hold the threads above the surface of the front roll as they pass from the rolls and means for supporting the guide.

6. In a spinning machine, in combination, 100 a front roll and a rear roll, means for supporting and driving said rolls to wrap threads thereon, a guide arranged in front of said front roll over which guide the threads are adapted to pass, the upper surface of said front roll being arranged beneath a straight line connecting the upper surface of the rear roll and said guide, whereby the threads are lifted out of contact with said front roll as they pass to said 105 guide, and means for supporting the guide.

7. In a spinning machine, in combination, a front roll and a rear roll, means for supporting and driving said rolls to wrap threads thereon, a guide arranged in front 115 of said front roll over which the threads are adapted to pass after leaving said rolls, said guide being inclined to the axis of said front roll, and being positioned to hold the threads out of contact with said front roll 120 as the same pass from the rolls.

8. In a spinning machine having front and rear rolls and an inclined guide arranged between and parallel with said rolls, the improvement which comprises a guide 125 arranged in front of said front roll and above the axis thereof, said guide being inclined in substantially the same direction as the aforementioned guide between said rolls.

9. In a spinning machine having front 130

- and rear rolls with the upper surface of the latter arranged above the upper surface of the former and also having an inclined guide arranged between said rolls, the improvement which comprises a guide arranged in front of said front roll and having its upper surface so positioned that a straight line extending therefrom to the upper surface of said rear roll will pass above said front roll, said guide being inclined in substantially the same direction as the aforementioned guide between said rolls.
10. In a spinning machine, in combination, a front roll and a rear roll, means for driving said rolls to wrap threads thereon, a guide arranged in front of said front roll for receiving the threads as they leave said rolls, the upper surface of said front roll being positioned below a plane parallel with
- the axis of said rear roll and passing 20 through the upper surface of said rear roll and said guide, whereby the threads are lifted out of contact with the front roll in passing from the rear roll to said guide.
11. In a spinning machine, in combination, two feed rolls arranged adjacent to each other, means for rotating said rolls to wrap thread thereon, a guide arranged adjacent one of said rolls over which guide the thread is adapted to pass as it is leaving 30 the rolls, said guide being positioned to hold the thread away from the surface of the roll adjacent to which it is arranged as the thread passes from the rolls.

In testimony whereof I hereunto affix my 35 signature.

RICHARD V. BUTLER.
